UNITED STATES PATENT OFFICE.

CHARLES EDWARD HAVILAND, OF LIMOGES, FRANCE.

DESIGN FOR A DISH.

SPECIFICATION forming part of Design No. 22,230, dated February 21, 1893.

Application filed January 13, 1893. Serial No. 458,301. Term of patent 14 years.

To all whom it may concern:

Be it known that I, CHARLES EDWARD HAVILAND, a citizen of the United States, residing at the city of Limoges, in the Republic of France, have invented and produced a new and original Design for a Dish and other Articles, of which the following is a specification, reference being had to the accompanying drawings, forming part thereof, and in to which—

Figure 1 is a top view of a dish bearing my design; and, Fig. 2 is a detached longitudinal section of same on the dotted line 2—2 of Fig. 1.

15 The leading features of my design consist of the shape of the rim and adjoining portions of the bottom of the dish and the ornamental configurations thereof, as illustrated in the accompanying drawings. The rim of 20 the dish is lettered A, and as shown in Fig. 1, the said rim is oval in outline and is composed at opposite sides of the dish of the scalloped sections B, C, while at the ends of the dish the said rim is composed of the smaller 25 and more uniform scalloped sections D. At the ends of the dish the rim A curves downward below the horizontal upper surface of the bottom E, as indicated in Fig. 2, forming an ornamental depression F and producing 30 a shell-like effect at the ends of the dish.

From the depression F at each end of the dish, the tapering grooves G extend along the base of the rim A for a definite distance, as shown, and finally merge into the horizontal upper surface of the bottom E, which at opposite sides, meets, by graceful lines, the lower edge of the rim A. The surface ornamentation is, as illustrated in Fig. 1, applied to that portion of the rim A occupied by the uniform scallops D constituting the opposite ends of 40 the dish, and this ornamentation consists of the scrolls H, I, bearing at their upper ends the scalloped edges J, the latter being in relief. Below the scrolls H, I, is applied the ornamental ribbon scroll K, the latter being 45 also in relief and terminating at opposite ends in the foliate sprays L. The scrolls H, I, with the edges J combine with the depressions F to produce an ornamental conventionalized shell-effect at the ends of the dish. 50

What I claim is—

The design for a dish or other article, substantially as shown and described.

Signed at the city of Limoges, in the Republic of France, this 27th day of December, 55 1892.

CHARLES EDWARD HAVILAND.
